UNITED STATES PATENT OFFICE.

CLAUDE BEAVER, OF FISHERS, INDIANA.

GUN-SIGHT.

1,238,379.

Specification of Letters Patent. Patented Aug. 28, 1917.

Application filed April 24, 1916. Serial No. 93,293.

To all whom it may concern:

Be it known that I, CLAUDE BEAVER, a citizen of the United States, residing at Fishers, in the county of Hamilton and State 5 of Indiana, have invented a new and useful Gun-Sight, of which the following is a specification.

It is the object of my invention to provide an adjustable gun sight, which can be 10 adjusted for distance, for wind deflection, and for visual peculiarities of the user; and in which the adjustments can be made readily, with the gun in position to be raised, and on scales which are easily and conveniently 15 visible.

The accompanying drawing illustrates my invention. Figure 1 is a perspective view of a gun sight embodying my invention, showing a fragment of the gun barrel on 20 which it is mounted; Fig. 2 is an enlarged section through the outer end of the sight-carrying arm; Figs. 3 and 4 are sections on the lines 3—3 and 4—4 respectively of Fig. 2; Fig. 5 is an elevation of the outer end 25 of the sight-carrying arm, taken from the same point of view as Fig. 2; Fig. 6 is a plan of the parts shown in Figs. 2 and 5; and Fig. 7 is an enlarged section through the spring latch controlling the distance adjustment. 30

Mounted on the gun barrel 10, which is of any desired character and is provided with any suitable front sight 11, is the base plate 12 of my improved rear sight, which is held 35 to the gun barrel 10 in any manner, as by screws 13. At the forward end of this base plate 12 is hinged a sight-carrying arm 14, which projects upwardly and rearwardly therefrom at an adjustable angle. A link 40 15 is pivoted at its forward end to an intermediate point on the sight-carrying arm, and at its rear end to a slide 16 which overlaps the edges of the base plate 12 and is slidable forwardly and rearwardly thereon. 45 By this sliding the angle at which the sight-carrying arm 14 stands is adjustable through about 90°. The left hand edge of the base plate 12 is provided with teeth 17 which 50 operate with the down-turned end of a latch lever 18 which is pivoted on the slide 16 and has a cross arm extending over such slide and provided at its right hand end with a button 19 in convenient position to be engaged by the user's right thumb. The latch 55 lever is pressed into engagement with the

teeth 17 by a suitable spring 20 acting on the under side of the cross arm. The rear edge of the slide 16 is provided with a pointer 21 which travels over a scale 22 on the base plate 12 as the slide 16 is adjusted, such 60 scale being suitably graduated for the distance of the object aimed at. This scale 22 is visible with the gun in position to be raised to the shoulder, so that the distance adjustment may be obtained by merely pressing the button 19 by the right thumb and moving the slide 16 along the scale 22 until the pointer 21 indicates the proper distance. 65

The upper end of the sight-carrying arm 14 is provided with a transverse groove 25, 70 in which is mounted a transversely moving slide 26 having a finger 27 which projects between the two bifurcations 28 with which such sight-carrying arm 14 is provided; and a screw 29 extends through such bifurcations 75 and has a threaded engagement with the finger 27. By turning the knob 30 at the right hand end of the screw 29, the slide 26 is moved transversely of the gun barrel. The knob 30 is operable by the user's right 80 thumb and finger, with the gun either at the shoulder or in position to be raised thereto, and the slide 26 is provided with a scale 31 which by the movement of such slide travels under a pointer 32 on that side 85 of the grooved end of the sight-carrying arm 14 which is toward the user. The scale 31 is suitably graduated to indicate corrections for wind deflection, which corrections are made by the adjustment of the slide 26. 90

The slide 26 is provided with a slot 35 parallel to the groove 25, and a right and left hand screw 36 operable by a knob 37, conveniently at the left, is mounted in such slot and engages the inturned fingers 38 and 95 39 of two sight members 40 and 41 so as to move them toward and from each other by the turning of the screws 36. These sight members 40 and 41 are portions of cylinders fitting on the outside of the slide 26, and the member 40 has a tongue 42, cylindrical exteriorly, which underlies the member 41. The sight slot 43 is formed by the adjacent edges of the sight members 40 and 41 and the outer surface of the tongue 42, and may 100 be adjusted in width to suit the visual peculiarities and fancies of the individual user. Because the tongue 42 is cylindrical exteriorly, its outer surface is always at the same distance from the axis of the screw 36 105 110

regardless of the adjustment of the slide 16. The fingers 38 and 39 are enlarged at their ends, and the slot 35 is undercut, so that the sight members 40 and 41 and the screw 36
 5 are interlocked within such slot; but to permit the removal of said sight members and screw when desired, the narrow upper part of the slot 35 has two cut out portions 44 transverse to the slot proper, with which cut
 10 out portions the fingers 38 and 39 may be made to register by proper manipulation of the knob 37, such registering occurring when the slot 43 is wider than it would ever be in actual use. If desired, a scale 45 may
 15 be provided on the transverse slide 26 to cooperate with indicating fingers 46 on the sight members 40 and 41; but ordinarily this scale is not necessary, as the average gun user prefers to adjust the width of his sight
 20 slot to suit his own fancy independently of any scale.

Thus by moving the slide 16 forwardly or rearwardly the sight may be raised or lowered to adjust for distance, which is indicated on the scale 22 so that the adjustment
 25 can be made easily and with the gun in position to be raised; by turning the knob 30 the transverse slide 26 and with it the sight slot 43 may be moved to the right or left to compensate for wind deflection, the proper adjustment being indicated on the scale 31 which is visible even with the gun at the shoulder; and by turning the knob 37 the slot 43 may be adjusted to suit the
 30 fancy of the user. The first two of these adjustments are made with the right hand, since they are the ones which would require to be made rather promptly. The third adjustment is made with the left hand, since
 35 it would ordinarily not have to be changed frequently.

I claim as my invention:

1. A gun sight, comprising a sight-carrying arm pivoted at its forward end, a forwardly and rearwardly moving slide in the rear of said sight-carrying arm, a link connecting said slide and an intermediate point on said sight-carrying arm, the free end of said sight-carrying arm being provided with
 45 a transverse groove, a transversely moving slide mounted in said transverse groove provided with a sight, and a screw coöperating with said sight-carrying arm and said transversely moving slide for moving the latter
 50 along said transverse groove.

2. A gun sight, comprising a sight-carrying arm pivoted at its forward end, a forwardly and rearwardly moving slide in the rear of said sight-carrying arm, a link connecting said slide and an intermediate point on said sight-carrying arm, a sight at the free end of said sight-carrying arm, and a spring latch carried by said forwardly and rearwardly moving slide for holding it in
 60 any position.

3. A gun sight, comprising a sight-carrying arm pivoted at its forward end, a forwardly and rearwardly moving slide in the rear of said sight-carrying arm, a link connecting said slide and an intermediate point on said sight-carrying arm, the free end of said sight-carrying arm being provided with a transverse groove, a transversely moving slide mounted in said transverse groove provided with a sight, a screw coöperating with
 70 said sight-carrying arm and said transversely moving slide for moving the latter along said transverse groove, and a spring latch carried by said forwardly and rearwardly moving slide for holding it in any 80 position.

4. A gun sight, comprising a sight-carrying arm pivoted at its forward end, a forwardly and rearwardly moving slide in the rear of said sight-carrying arm, a link connecting said slide and an intermediate point on said sight-carrying arm, the free end of said sight-carrying arm being provided with a transverse groove, a transversely moving slide mounted in said transverse groove provided with a sight, a screw coöperating with
 85 said sight-carrying arm and said transversely moving slide for moving the latter along said transverse groove, and a spring latch carried by said forwardly and rearwardly moving slide for holding it in any 90 position, said latch having a release button and said screw an operating knob at the same side of the device.

5. A gun sight, comprising a member 100 grooved transversely to the line of sight, two sight members forming between them a sight slot and having fingers projecting into the groove in said member, and a right and left hand screw engaging said fingers so that by 105 turning said screw the members are moved oppositely to vary the width of the sight slot.

6. A gun sight, comprising a member grooved transversely to the line of sight, two sight members forming between them 110 a sight slot and having fingers projecting into the groove in said member, and a right and left hand screw engaging said fingers so that by turning said screw the members are moved oppositely to vary the width of 115 the sight slot, said transverse groove being undercut and the inner ends of said fingers being enlarged so as to interlock the sight members in the groove.

7. A gun sight, comprising a member 120 grooved transversely to the line of sight, two sight members forming between them a sight slot and having fingers projecting into the groove in said member, and a right and left hand screw engaging said fingers 125 so that by turning said screw the members are moved oppositely to vary the width of the sight slot, said transverse groove being undercut and the inner ends of said fingers being enlarged so as to interlock the sight 130

members in the groove, and said transverse groove being provided with enlarged portions extending from the inner part to the edge of the groove, with which enlarged portions of said fingers may be made to register to permit their removal.

8. A gun sight, comprising a pivoted sight-carrying arm, two sight members mounted on the free end of said sight-carrying arm and forming between them a sight slot, said members being movable oppositely to vary the width of said sight slot, one of said sight members having a portion which underlies the other and forms the base of

said sight slot and which has a cylindrical 15 surface where it forms said sight slot base.

9. A gun sight, comprising a pivoted sight-carrying arm adjustable to various angles, a transversely moving slide carried by the free end of said arm, and two sight 20 members carried by said slide and adjustable oppositely along said slide.

In witness whereof, I have hereunto set my hand at Indianapolis, Indiana, this 20th day of April, A. D. one thousand nine hundred and sixteen.

CLAUDE BEAVER.
